DESIGN FOR A WALLPAPER OR THE LIKE

William Burton, River Forest, Ill., assignor to United Wallpaper, Inc., Chicago, Ill., a corporation of Delaware

Application November 28, 1947, Serial No. 142,868

Term of patent 3½ years

(Cl. D59—10)

To all whom it may concern:

Be it known that I, William Burton, a citizen of the United States, residing at River Forest, in the county of Cook and State of Illinois, have invented a new, original, and ornamental Design for a Wallpaper or the like, of which the following is a specification, reference being had to the accompanying drawing, forming a part thereof.

In the drawing the figure is a plan view of a wallpaper or the like, showing my new design.

The dotted lines outline a design unit, which unit is repeated over the wallpaper or the like, as indicated by the extensions beyond the unit boundaries.

I claim:

The ornamental design for a wallpaper or the like, substantially as shown and described.

WILLIAM BURTON.
